UNITED STATES PATENT OFFICE.

BERTRAM C. KENYON, OF MISHAWAKA, INDIANA, ASSIGNOR OF ONE-HALF TO DODGE MANUFACTURING COMPANY, OF MISHAWAKA, INDIANA, A CORPORATION OF INDIANA.

ROTATING-CYLINDER GAS-ENGINE.

1,227,452.

Specification of Letters Patent.

Patented May 22, 1917.

Application filed March 14, 1914. Serial No. 824,776.

To all whom it may concern:

Be it known that I, BERTRAM C. KENYON, citizen of the United States, residing at Mishawaka, in the county of St. Joseph and State of Indiana, have invented certain new and useful Improvements in Rotating-Cylinder Gas-Engines, of which the following is a specification.

My invention relates to improvements in 10 rotating cylinder engines and it more especially appertains to the features pointed out in the annexed claims.

The purpose of my invention is to provide a revolving cylinder internal combustion engine which comprises an even number of multiple cylinders arranged in opposition to each other, in which the pistons are cast in pairs and so formed about midway thereof that they may slide past each other, 15 performing their functions, without interference. Another purpose is to form an engine without the usual tie rods, connecting rods, etc. Also an engine that is simple to build and operate and will not set up 20 periodic vibrational disturbances.

With these ends in view I illustrate in the accompanying figures such instances of adaptation as will disclose the broad features of my invention without limiting myself to the specific details shown.

Figure 1. is a side elevation.

Fig. 2. shows the valve end of the engine partly in section.

Fig. 3. is an elevation in section, on a plane 35 parallel to the axis of the shaft.

Fig. 4. is an end elevation of the central portion of a pair of pistons and the driving block, standing in a vertical position.

Fig. 5. is a similar view of a pair of pistons 40 standing in a horizontal position.

Fig. 6. is a perspective view of a pair of double ended pistons in their assembled relation but removed from the cylinders.

Fig. 7. is an end elevation of a modified 45 form of construction in which the four cylinders may be cast in one piece.

Fig. 8. is an elevation showing how two cylinders may be cast in one piece.

Fig. 9. is a diagrammatic view showing 50 an approximate relation of the cams and valve stems.

A suitable base frame A has standards α and α' formed thereon. The standard α' terminates in a "bearing" adapted to receive 55 one end of the crank shaft B that is secured

therein against rotation by key b . External of this "bearing" an annular channel α^2 is formed by an inner wall α^3 that encircles the shaft B and an outer wall α^4 . Into the channel α^2 the delivery pipe c of the carburetor C is led.

The driving end of the engine is supported on a two-part bearing of the standard α , in which a "trunnion" extension d of the crank casing head D' rotates. Suitable 65 antifriction metal is placed internally and externally of the bearing portion, d . A suitable driving flange d' may be cast integrally with the part d . The flange, in connection with the face of casing head D' 70 serves the purpose of preventing endwise displacement of the moving parts. The flange d' may be formed with a centering shoulder d^2 and suitable holes d^3 to support a sprocket wheel or other driving means. 75

The electric ignition system E is supported on the bearing α^5 and insulated therefrom, in any suitable manner. It terminates in a pointed sparking point e placed a slight distance from the cylinder 80 spark plugs f^3 which successively pass this point as the cylinders are revolved around the stationary crank shaft B.

The crank casing D may be made in two parts secured to each other by bolts d^4 (Fig. 85 1). When assembled, the crank space d^5 is found to form a separate chamber from the cam space d^6 through a partition d^7 . In the outer space d^6 the inlet and exhaust cams are placed as well as the two-to-one gears 90 for actuating the same. A hub d^8 is cast on the partition d^7 having a slightly larger inside diameter than the shaft B in order that any desirable anti-friction metal may be placed between them as this forms the second 95 bearing on which the cylinders revolve.

A "spider" d^9 which contains the fuel passages d^{10} is secured to the partition d^7 in any suitable manner so that properly gasketed joints are made and gas-tight joints 100 where the hub of d^9 rotates against walls α^3 and α^4 of the keyed-end of the shaft B. As the pressure in the ducts d^{10} is not great the joints need not be provided with stuffing boxes.

An intermediate gear shaft d^{11} has bearing at one end in a projection d^{12} cast onto the partition d^7 and at the other end it rotates in a hole of d^9 . This shaft carries two gears d^{13} and d^{14} . The first one meshes 110

2

with a toothed gear ring b' fastened to the stationary shaft B and as gear d^{13} is carried around b' by the rotating cylinders it may revolve at a ratio of 1:1. Gear d^{14} meshes 5 with a toothed ring d^{15} at a resulting ratio of 2:1 and rotates on hub d^8 carrying with it the differentially placed valve operating cams d^{16} and d^{17} . These cams positively control the valve stems f which are practical duplicates of each other—one set operates the inlet and the other the exhaust valves. This action is transmitted to the conical puppet valves f' and f^2 that are supplied with the usual valve stems which 10 emerge from the cylinder heads through reinforcing and guiding bosses. They are kept closed by the coil springs and opened when required by the cycle of operations by means of rocking yokes f^3 secured to rock 15 shafts f^4 . Yokes f^3 are fastened to the other end of the rock shafts f^4 and the valve stems f when moved by the cams d^{16} and d^{17} press against their under side and alternately open and close the valves f' and f^2 .

20 Behind each of the valves, pockets are cast, which in the case of the valve f' connect with fuel passages F' , d^{10} and d^2 and for valves f^2 connection is made through openings f^6 to the open air, serving as the 25 exhaust outlets. Connected by openings f^8 with the inside of the cylinders F adjacent pockets f^7 are formed. Into these the spark 30 plugs f^9 project. The cylinders are fastened to the crank casing D by means of bolts and they are held central through an 35 annular projection f^{10} . Valve stems f are actuated by the cams d^{16} , d^{17} in any suitable manner, through roller ends or otherwise. This construction insures positive valve 40 action and in order to provide a take up for wear, one or both of the rods of each cylinder may have a means for adjustment at its upper end, or set screws could be placed in the ends of yokes f^3 and f^5 , the exact form 45 of such take-up being of secondary importance, it being probable that with proper initial care in fitting and adjustment no take-up would be required. Such means being well understood they are not shown in 50 the drawings.

The double ended integrally formed pistons G are provided with cup shaped heads, g , piston rings g' and a central enlargement g^2 of rectangular shape, surrounding a rectangular slot or opening g^3 . Between the heads g one-half of the piston body is removed at g^4 , (practically slightly more than one-half to allow for working clearance). The enlargement g^2 projects beyond the piston 55 diameter in two directions parallel with the face g^4 and suitable provision therefor is made within the crank casing D.

In the slots g^3 a sliding block b^2 is placed reaching across both slots of the two adjacent pistons and encircling crank pin b^3 .

formed on crank disk b^4 . The outer end of this pin b^3 is tapered so as to seat in a conical hole formed in crank disk b^5 and is held against rotation in any suitable manner.

With this form of construction the greatest possible simplicity of parts is secured and a uniform exploding position maintained which with rigidly connected pistons, an absence of rods, etc., is free from the cumulative vibrational disturbances usually found in evenly numbered multiple cylinder engines having variable positions of cylinder ignition.

Since the cycle of operations is such as are common to four-cycle engines it is thought unnecessary to describe the sequence of movements any further than to state that the order of progression is continuously rotative through the orderly movement of the cylinders F in rapid succession past spark 80 point e . Thus maintaining a uniform direction of thrust that is of vital importance in high speed service. In Fig. 2 it will be seen that the upper piston is at its extreme distance from the center of rotation 85 and its companion is the nearest thereto while the two pistons, shown in horizontal relation are in a mid-position having passed over one-half of their maximum traverse. The direction of rotation will obviously be 90 controlled by the "forward" or "back" position of the sparking point e .

Any suitable take-up for wear, for instance with wedges, etc., as shown in Figs. 4 and 5 may be combined with cross-head 100 blocks b^2 . If desired the cylinders may be cast two and two-together as shown in Fig. 8 by joining them diagonally through the end wall d^7 . Or they may be cast in one piece if the cylinder heads are removable, as 105 shown in Fig. 7. Projections d^4 , shown in Figs. 1 and 2 may be carried the full width of the crank chamber casting D but ordinarily they will serve as a suitable fastening for head D' if of ear-shape as shown.

The valve stems may have outer guide blocks, as f^{11} that co-act with the inner guides formed on each side of spider legs d^9 . If it is found desirable to have the valve stems f stand radially to the axis of 115 rotation the legs d^9 may be enlarged side-wise at the point where the stems cross the ducts d^{10} so as to form unobstructed passage ways there around.

What I claim is;

1. In gas engines, a plurality of pairs of rotatable cylinders revolvable in the same plane, a two-part support in common for all the cylinders, a pair of heads integrally formed and constituting a piston and operable in one pair of cylinders, and having bearing in the cylinders substantially throughout the length of the piston, another piston similarly operable in another pair of cylinders, a rectangular enlargement to 120 125 130

- each piston, a segmental prism joining each pair of heads and an enlargement forming lengthwise recesses of segmental shape between the heads extending to the flat face of each prism whereby a pair of pistons may slide adjacent each other within a space equal to the diameter of the cylinders, rectangular slots in the enlargements, a block 5 slideable simultaneously in all the slots, a stationary crank shaft having its crank pin within said block, bearings for the shaft in the cylinder support, and suitable means for holding the shaft against rotation.
2. In gas engines, a separable crank casting, a plurality of pairs of cylinders secured thereon opposing cylinders being in axial alinement with each other, a crank shaft, a suitable support, means for holding said shaft against rotation in the support, integrally connected piston heads comprising a central rectangular frame having a slot formed therein and joined to the heads by segmental prisms, each pair of heads forming a piston unit which is operable in a pair of said cylinders, and having bearing throughout the length of the piston, and means common to all the pistons and within the slots connecting the pistons to the crank shaft.
3. In gas engines, a suitable axially divided base, a crank shaft supported thereby and held from rotation, a plurality of diametrically opposed cylinders rotatable around the shaft, a rectangular frame having a slot therein, segmental prisms integral with the frame, rounded ends forming heads integral with the prisms and constituting a piston adapted to be slideable so as to have bearing throughout the length of the piston in diametrically opposed cylinders, another pair of cylinders, a similar prism-piston slideable therein, a crank pin, a block engaging said pin in common for all
- the slots, and means for holding two pairs of cylinders together as a unit group at an angle to each other whereby the prisms will be slideable face to face with their axes similarly disposed while moving on the same plane of rotation as the cylinders.
4. In gas engines, a suitable two-part casting comprising separate cylinders and a portion of an angular crank case to each part, means for holding the parts together to provide pairs of oppositely positioned cylinders in axial alinement with each other, rectangular frames having slots slideable in the crank casing, integrally formed segmental prisms projecting diametrically opposite each other from the frames and terminating in heads having the same radius as the arcs of the segmental prisms, a block slideable in a pair of slots simultaneously, a crank pin in the block, crank disks placed outside the inner face of the cylinder walls, a crank shaft connected therewith, and means for holding the same against rotation.
5. In gas engines, a suitable support, an inclosed angular crank casing, a plurality of rotatable cylinders secured thereon, a crank shaft held stationary in the support, connected heads forming a double ended piston slideable in two oppositely positioned cylinders, another group of cylinders and a piston therefor, and rectangular enlargements about midway of the length of the pistons the same being held in alinement by the crank casing and joined to the heads by segmental prisms integral therewith, a pair of prisms equaling the diameter of the pistons.
- In testimony whereof I affix my signature in presence of two witnesses.
